Primary Examiner—Celia Murphy(74) *Attorney, Agent, or Firm*—Scott B. Garrison**CLAIM**

We claim the ornamental design for a shoe cover traction pattern with heel and toe areas, as shown and described.

DESCRIPTION

FIG. 1 is a perspective view of a shoe cover shown in use to depict the environment of our new design for a shoe cover traction pattern with heel and toe areas;

FIG. 2 is a perspective view of a shoe cover traction pattern with heel and toe areas, showing our new design; and,

FIG. 3 is a bottom plan view thereof.
 The broken lines showing portions of a shoe, shoe cover, and shoe cover pattern in FIGS. 1-3, respectively, are environmental only and form no part of the claimed design.
